Primary Examiner — Susan Bennett Hattan*Assistant Examiner* — Marie Fast Horse*(74) Attorney, Agent, or Firm* — Cantor Colburn LLP(57) **CLAIM**

We claim, the ornamental design for a stand for telephone, as shown and described.

DESCRIPTION

FIG. 1 is a front perspective view of a stand for telephone showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another front perspective view thereof, in which the stand for telephone is shown in a telephone environment;

FIG. 9 is another side view thereof, in which the stand for telephone is shown in another position; and,

FIG. 10 is another side view thereof, in which the stand for telephone is shown in another position.

The broken lines in the drawings depict environmental structure only and form no part of the claimed design.
